ATVS.

UNITED STATES PATENT OFFICE.

PERLEY H. BROWN, OF HUDSON, MASSACHUSETTS, ASSIGNOR TO APSLEY RUBBER COMPANY, OF HUDSON, MASSACHUSETTS, A CORPORATION OF MASSACHUSETTS.

SHOE.

1,306,996.

Specification of Letters Patent. Patented June 17, 1919.

Application filed October 12, 1918. Serial No. 257,853.

To all whom it may concern:

Be it known that I, PERLEY H. BROWN, a citizen of the United States, residing at Hudson, county of Middlesex, State of Massachusetts, have invented a certain new and useful Improvement in Shoes, of which the following is a specification, reference being had therein to the accompanying drawings.

- 10 My invention relates to a new and improved shoe of a character which can be manufactured by the methods commonly employed in a rubber shoe factory as distinguished from methods commonly employed in a leather boot and shoe factory. The particular object of the invention is to provide a heavy work shoe preferably having a canvas upper and a fiber outsole having the general appearance of a leather boot or shoe of the Goodyear or McKay type. The shoe embodying my invention is of strong, durable construction, very easy for the wearer and can be manufactured at a relatively small price.
- 15 The invention will be fully understood from the following description when taken in connection with the accompanying drawings and the novel features thereof will be pointed out and clearly defined in the claims at the close of this specification.

In the drawings, Figure 1 is a side elevation partly in section of a shoe embodying my invention.

Fig. 2 shows the shoe with the upper pulled over the last and insole and the filler piece in place.

Fig. 3 is a plan view of a shoe in the condition shown in Fig. 2.

Fig. 4 shows the shoe after the application of a frictioning material to the in-turned margin of the upper and the filler.

Fig. 5 shows the shoe after the middle sole has been applied.

Fig. 6 is a plan of the shoe shown in Fig. 5. At 11 in the several figures is shown the upper of the boot or shoe. This is preferably of canvas or other fabric material such as is commonly used in the manufacture of sneakers, tennis shoes and work shoes which

50 are manufactured in a rubber factory. The upper may be of any desired shape and cut. In the drawings, I have shown an upper for a blucher having a vamp 12 and tip 13. At 14 is shown an insole which is preferably

composed of stiff material such as leather or fiber board. A metal shank 15 may be used if desired. The insole 14 is laid on a metal faced last 4 and the upper 11 is then pulled over and the margins secured to the insole in any suitable manner, as by tacks 16, the points of which are clenched against the last or by rubber cement. This pulling over and lasting operation may be done by a pulling over or lasting machine or by hand as may be more convenient. A filler piece 17 to level up the shoe is then laid in place being stuck down with cement. Thereafter the in-turned margin of the upper and the bottom surface of the filler piece 17 is covered with frictioning material comprised of rubber dissolved in a suitable solvent. This layer of frictioning material is designated 18 in Fig. 4. Thereafter a middle sole 19 composed of a flat piece of high grade rubber stock preferably containing fabric is laid in place. This stock is in a tacky adhesive condition when put in place. It is then secured in part by tacks 20 which follow the margin of the shoe and pass through the upper and insole. The middle sole is also secured by the adhesion resulting from the subsequent vulcanization of the frictioning material. After the middle sole has been secured in place an outsole 23 which may be provided with a heel 24 is put in place. This outsole is cut from a sheet of vulcanizable fiber stock of the kind now commonly employed for soles of boots and shoes and protrudes beyond the margin of the middle sole so that the shoe has something the appearance of a Goodyear welt shoe as distinguished from the ordinary sneaker or tennis shoe in which the outsole is in part secured to the upper by means of a foxing of rubber following the line of contact between the upper and the sole. After the outsole has been put in place, it is pressed firmly onto the shoe and the entire shoe is vulcanized preferably by the dry cure in the manner well known to rubber shoe manufacturers.

From the foregoing it will be seen that the shoe embodying my invention is provided with a fiber outsole secured to the remainder of the shoe by the adhesion resulting from vulcanization. The margin of the said outsole protrudes to give the shoe the desired appearance and some of the ad-

vantages of the Goodyear welt shoe as for instance the protection of the upper by the protruding edge of the sole.

What I claim is:

- 5 1. A shoe comprising an insole, an upper secured to the insole by permanent fastening devices, a middle sole of vulcanizable material secured to the under side of the insole and lapping over on to the turned in portion 10 of the upper and vulcanized thereto, and an outer sole vulcanized to the said middle sole and having a marginal portion which projects beyond the edge of the said middle sole.
- 13 2. A shoe comprising an insole, an upper secured to the insole by permanent fastening devices, a filler on the under side of the insole within the margin of the upper, a middle sole of vulcanizable material applied 20 to the under side of the said filler and lapping over on to the turned under part of the upper outside of the margin of the filler and covering said fastening devices of the upper and insole, and an outer sole of vul- 25 canizable material, said middle sole being vulcanized to the outer sole and to the upper, the said outer sole having a marginal projecting portion which extends beyond the inturned portion of the upper and beyond 30 the margin of the middle sole.
- 33 3. A shoe comprising an insole of fibrous material, an upper secured to the insole by

permanent fastening devices, a filler on the under side of the insole within the margin of the upper, a coating of frictioning material covering the bottom surface of the filler and the inturned margin of the upper, a middle sole of vulcanizable material overlying the said frictioning material and vulcanized to the filler and upper, and an outer sole vulcanized to the said middle sole and having a marginal portion which projects beyond the edge of the said middle sole throughout its entire contour.

4. A shoe comprising an insole, a canvas upper secured to the insole by permanent fastening devices, a middle sole of vulcanizable material comprising a structure of rubber and fabric which is secured in part by fastening devices which follow the margin of the shoe and pass through the upper and insole and is also secured to the edge of the upper by vulcanization, and an outer sole of fibrous material which is vulcanized to the said middle sole and has a marginal portion which projects beyond the edge of said middle sole throughout the entire contour of said middle sole, said permanent fastening device between the upper and the insole being entirely concealed in the finished shoe.

In testimony whereof I affix my signature.

PERLEY H. BROWN.
